UNITED STATES PATENT OFFICE

2,579,387

FEED DRAIN AND SAFETY DEVICE FOR
WATER HEATERSLéon Le Bozec, Courbevoie, and Georges Gautier,
Mesnil-le-Roi, FranceApplication August 26, 1947, Serial No. 770,694
In France October 2, 1946

4 Claims. (Cl. 277—20)

1

The object of our invention is a feed, drain and safety device adapted to be used in a water-heater and which is intended to be inserted between said water-heater and the water inlet ductor pipe.

Our device comprises a water inlet valve and a water outlet valve which valves are both controlled by means of a common shaft adapted to carry out a combined translational and rotational movement due to the provision of a lug engaged in a slot the pitch of which, with reference to the said shaft varies from one end to the other end of said shaft.

According to a preferred embodiment the locking of the inlet valve is obtained by means of an adjustable stop-screw, inserted between the control shaft and said inlet valve.

Our invention will be best understood with reference to the annexed drawings in which we have illustrated a number of embodiments of the said invention, and in which:

Figs. 1 to 7 show a first embodiment, Figs. 1 and 2 being vertical sections along two planes at right angle one to the other, and showing the parts in the respective positions corresponding to the blocked condition of the inlet valve, Figs. 3 and 4 being views similar to Figs. 1 and 2 but corresponding to the normal unblocked position of the inlet valve, Figs. 5 and 6 being similar views, corresponding to the drain position and Fig. 7 showing on a larger scale the slot used to guide the control shaft of the device.

Fig. 8 shows a modification relating to the adjustment of the outlet pipe.

Fig. 9 shows in vertical partial cross-section a modification in the adjustment of the said outlet pipe, and

Fig. 10 shows in axial cross-section a device in which the adjustment of the inlet valve is obtained by means of a screw adapted to be operated from the outside of the device.

The device shown in Figs. 1 to 7 comprises a body 1 provided with three externally threaded pipe-stubs of which stub 2 is to be connected with the water inlet pipe, stub 3 is to be connected with the water heater to be fed and stub 4 is to be connected with an outlet pipe.

On body 1 is fixed by means of screws 5 an outer flange of a sleeve 6 in which there is mounted a shaft 7 provided with a packing-box 8 and controlling hand-wheel 9. Said hand-wheel 9 is provided with a pointer 11, the end of which is adapted to be moved on a scale 12.

Shaft 7 is adapted to slide axially as well as to rotate within sleeve 6. For such purpose the said shaft is provided with a lug 13 cooperating with a guide-slot 14 in sleeve 6. The said slot comprises part e f which is at a considerable angle to a longitudinal section of sleeve 6. Part e f of slot 14 is followed by another part f g of

2

the same slot at a quite low angle to a longitudinal section of sleeve 6, point g being located at the middle of the inclined course of lug 13. From g to h slot 14 is directed along a longitudinal section of sleeve 6.

Inlet valve 15, located in stub 2, is urged towards its closed position by a weak spring 16 bearing on a shoulder of sleeve 6.

The stem of valve 15 is guided within sleeve 6. A screw 17 carried on shaft 7 is adapted to engage the said valve stem.

In stub 4 is provided a valve 19 intended to operate as a drain valve and as a safety valve. Valve 19 is integral with a stem 21 controlled by means of a cam 22 on shaft 7.

The said valve 19 is provided with a return spring 23 bearing on a threaded ring 24. Ring 24 screws in an inner thread of stub 4, due to which the calibration of spring 23 may be adjusted by turning ring 24.

In order to make impossible that spring 23 be excessively compressed by operating ring 24, a circular groove 25 has been machined at the inside of stub 4 so that the upper edge of said groove acts as a stop for ring 24. Spring 23 bears on a circular disc carried by ring 24 at mid-height of said ring, in such a manner that ring 24 may be turned upside down without changing the calibration of the spring.

Such a device may be operated in the following manner:

Supposing that lug 13 is opposite point g in slot 14, corresponding to pointer 11 pointing at the mark 90° on scale 12, cam 22 and the remaining parts are in the respective positions shown in Figs. 1 and 2.

Screw 17 then bears on the stem of inlet valve 15, which is thus strongly pressed on its seat, so that no water can be let in.

Moreover, cam 22, which is in the position shown in Fig. 2, is out of engagement with stem 21 and the outlet valve 19 is thus closed.

To bring the device into normal position, hand-wheel 9 is rotated from the 90° position towards the 0° position. As lug 13 travels from g to f the head of screw 17 moves to the right side in Fig. 1 by a distance as shown at a (Fig. 7) said distance being sufficient for stopping the compression of the resilient packing of inlet valve 15.

If the movement of handwheel 9 is then carried on towards the 0° indication lug 13 travels from f to e in slot 14 and consequently shaft 7 and screw 17 execute in sleeve 6 an axial movement the length of which equals b (Fig. 7) due to which movement valve 15 is released. Valve 15 is then pressed on its seat only by the weak spring 16 and therefore acts as a free swinging valve. This corresponds to the normal position shown in Figs. 3 and 4.

If the water pressure in the inlet duct con-

nected to stump 2 exceeds the pressure inside of the water heater plus the weak pressure due to spring 16, valve 15 is formed from its seat, which allows for the feeding of the water heater to be supplied.

In the position shown in Figs. 1 and 2 and marked 90° (lug 13 opposite point g) if it be desired to empty the water heater, the handwheel is rotated towards the 180° mark, thus shifting lug 13 from g to h. Shaft 7 then rotates without any axial progress in sleeve 6, valve 15 remains in the closed position and cam 22 engages stem 21, pushing it in such a manner that valve 19 is opened. This is the drain position shown of Figs. 5 and 6 and corresponding to the 180° indication, lug 13 being then at point h.

The device being in the normal position shown in Figs. 3 and 4 (lug 13 being at point g) if the internal pressure raises above the nominal maximum for which spring 23 was calibrated, valve 15 is strongly pressed on its seat, while valve 19 is opened under the action of the said pressure, thus pressing on spring 23. Valve 19 then operates as a safety valve and allows for a determined amount of water flowing out, which brings again the internal pressure to a normal value.

The calibration of the spring 23 of the drain valve may be obtained by any suitable means.

For instance, a threaded sleeve 28 (Fig. 8) provided with a milled flange 29 may be used.

Moreover, instead of providing on shaft 7 a thrust screw acting on the inlet valve, the thrust screw 17 may, as shown in Fig. 9, be supported on the valve stem, the said stem being adapted to slide axially in shaft 7.

As shown in Fig. 10, a screw 31 may also be used, as an adjustable thrust member, the threaded part of which is prolonged by means of a smooth rod 32 extending within the control shaft to the outside of the device, by passing through a packing-box 33. This allows for an easy adjustment of valve 15 at any time and in any position.

The device which is the object of our invention has the advantages of being easily manufactured, securely operated and readily adjusted.

Our invention is not intended to be limited to the particular embodiments shown by way of illustration and many auxiliary modifications may be used as regards the apparatus described in the scope of our invention as defined in the appended claims.

We claim:

1. A valve comprising a casing having an inlet port, a discharge port and a drain port, a valve stem guiding sleeve extending into said casing and having an inner end disposed opposite said inlet port, a valve stem rotatably and slidably mounted in said sleeve and having an inner end, said sleeve having a slot extending about a part of its circumference with at least a portion thereof of helical form, a stud carried by the valve stem and positioned in said slot for imparting axial movement to said stem upon rotation thereof, a valve member slidably mounted in the inner end of said sleeve and engaged by the inner end of the stem for closing the inlet port, a spring loaded valve element closing the drain port, and a cam on said stem cooperating with the spring loaded valve for opening the latter.

2. A valve comprising a casing having an inlet port, a discharge port and a drain port, a valve stem guiding sleeve extending into said casing and having an inner end disposed opposite said inlet port, a valve stem rotatably and slidably

mounted in said sleeve and having an inner end, said sleeve having a slot extending about a part of its circumference with one portion of helical form, an adjoining portion of helical form of smaller pitch and a third portion lying in a plane perpendicular to the axis of the stem, a stud carried by the valve stem and positioned in said slot for imparting axial movement to said stem upon rotation thereof, a valve member slidably mounted in the inner end of said sleeve and engaged by the inner end of the stem for closing the inlet port, a spring loaded valve element closing the drain port, and a cam on said stem cooperating with the spring loaded valve for opening the latter, said stud and cam being so positioned relative to each other that the cam will engage the spring loaded valve when the stud is in the third portion of said slot.

3. A valve comprising a casing having an inlet port, a discharge port and a drain port, a valve stem guiding sleeve extending into said casing and having an inner end disposed opposite said inlet port, a valve stem member rotatably and slidably mounted in said sleeve and having an inner end, said sleeve having a slot extending about a part of its circumference with at least a portion thereof of helical form, a stud carried by the valve stem member and positioned in said slot for imparting axial movement to said stem member upon rotation thereof, a valve member slidably mounted coaxially within the inner end of said sleeve for closing the inlet port, a light spring urging the valve member to closed position regardless of the axial position of the stem and an adjustable stop carried by one of the stem and the valve members to engage the other member to positively urge the valve member to closed position.

4. A valve comprising a casing having an inlet port, a discharge port and a drain port, a valve stem guiding sleeve extending into said casing and having an inner end disposed opposite said inlet port, a valve stem rotatably and slidably mounted in said sleeve and having an inner end, said sleeve having a slot extending about a part of its circumference with at least a portion thereof of helical form, a stud carried by the valve stem and positioned in said slot for imparting axial movement to said stem upon rotation thereof, a valve member slidably mounted in the inner end of said sleeve for closing the inlet port, a light spring urging the valve member to closed position regardless of the axial position of the stem and an adjustable stop carried by the inner end of the stem for engaging the valve member to positively urge the latter to closed position, and having an actuating head extending axially through the valve stem to the exterior of said casing.
